RACEMIC ESTROGENIC COMPOUNDS

Ralph C. Tallman, Westfield, N. J., and Alfred H. Stuart, New York, N. Y., assignors to Schieffelin & Co., New York, N. Y., a corporation of New York

No Drawing. Application May 30, 1944,
Serial No. 538,089

5 Claims. (CL 260—619)

This is a continuation in part of our copending applications Serial Nos. 407,492 and 407,493 filed August 19, 1941, and contains common subject matter with our copending application 538,089 filed of even date herewith.

The present invention relates to substances possessing the action of the ovarian follicular hormone. Such action may be referred to as estrogenic action. This term is derived from the Greek word "estrus" which means the heat period in female animals and the follicular phase of the menstrual cycle in human females. The natural hormone or substance possessing the action thereof is necessary for normal functioning of the female menstrual cycle and the absence thereof may be accompanied by various pathological symptoms.

The ovarian follicular hormone obtained from natural sources, e. g. from the urine of pregnant female mammals, is too expensive to render it available for wide-spread use and the problem to the solution of which this invention is directed is the chemical synthesis of substances having a potency approaching or equal to that of the natural hormone so that such substances may be widely dispensed and the benefits flowing therefrom rendered available to a much larger group of patients than is possible in the case of the hormone obtained from natural sources.

In our copending application Serial No. 363,869, there is a disclosure of compounds having the general formula

and the use thereof as substitutes for the female follicular hormone. In that application those compounds are called Type V and it is pointed out that X may be selected from the group consisting of H, alkyl, acyl, and ester radicals of phosphoric or sulfonic acid, and that each R is alkyl.

Various species of this X radical are listed as follows for the purpose of illustration:

The radical OX may be in the ortho, meta or para position.

A study of this formula reveals that, considering the chain of three carbon atoms connecting the aromatic nuclei, the terminal carbon atoms must always be asymmetric while the middle carbon atom may or may not be. Therefore the number of possible stereoisomers will either be four or eight.

10 It has been discovered that it is possible to isolate from the conglomerate of isomers obtained by synthesis a single racemic mixture having a potency greater than that of the mixture or conglomerate of isomers.

15 It is therefore an object of this invention to isolate from the conglomerate of stereoisomers obtained by synthesizing compounds having the above general formula, a racemic mixture having a potency (expressed in terms of its action as a 20 substitute for the natural female ovarian follicular hormone) greater than that of the mixture or conglomerate from which said racemic mixture is isolated.

Having defined the substances generically, it 25 may be said that the various species are distinguished by the position and specific nature of the OX radical and the specific nature of the alkyl radicals R.

It has been discovered that, among the compounds having the above general formula, compounds having the formula

35 are particularly desirable. When compounds having this formula are synthesized a conglomerate or mixture of eight stereoisomers is obtained because each of the three carbon atoms in 40 the chain connecting the aromatic nuclei is asymmetric. It has been discovered that individual racemic mixtures may be isolated from this conglomerate having a potency higher than that possessed by the conglomerate of isomers.

45 Objects of the invention therefore include the following:

1. To synthesize compounds having the general formula

50 and to isolate from the conglomerate of stereoisomers thereby obtained, an individual racemic mixture having a potency greater than that of the conglomerate, in other words to obtain an individual racemic mixture of two compounds each having the above formula and to use it as a substitute for the ovarian follicular hormone obtained from natural sources.

2. To obtain a racemic mixture of two compounds each having the formula

3. To obtain a racemic mixture of two compounds each having the formula

4. To obtain a racemic mixture of two compounds each having the formula

5. To obtain a racemic mixture of two compounds each having the formula

6. To obtain a racemic mixture of two compounds having the formula

where A is an inorganic acid radical of the type represented by $-\text{SO}_4\text{H}$, $-\text{PO}_4\text{H}_2$.

It has been further discovered that the isolation of individual racemic mixtures from the conglomerate of isomers may be facilitated by the following general method:

First prepare an intermediate compound which we call a diphenyl propanone having the formula

where X has the definition given above. The processes set forth in the said application filed of even date herewith may be used for this purpose. Thus, as set forth in that application, the terminal group, OX, in the above formula may be a methoxy or any alkoxy group and may be obtained by using appropriate starting compounds in Step I. For example, the value of OX in the above formula will be methoxy when the appropriate starting compound, as illustrated herein-after, contains a methoxy group; OX will be alkoxy when the appropriate starting compound has an alkoxy group. In this way any alkoxy group may be obtained in the final product, or by converting the OH groups in the final phenolic compound.

The synthetic compound having this formula has two asymmetric carbon atoms and therefore four stereoisomers. It has been discovered that these may be separated into two racemic mixtures. Each of these mixtures may then be converted into a compound having the general formula set forth above and there will then be obtained, from each racemic mixture, four stereoisomers in the form of two racemic mixtures which may be separated. Thus instead of attempting to separate a conglomerate of four racemic mixtures (eight stereoisomers) the problem is simplified by separating two racemic mixtures.

There are several ways of producing various species of the above mentioned intermediate compound and converting it into a compound having the general formula above set forth. One method will be shown as follows for purposes of illustration. This will be done by first showing the reactions and then giving details for effecting them.

In Step I any suitable condensing agent may be used, e. g., hydrochloric acid. The intermediate compound produced as shown in Step II is in the form of two racemic mixtures, one liquid and one solid. These mixtures are separated preferably by dissolving the two mixtures in a solvent, e. g., alcohol, and separating the solid racemic mixture by crystallization. The melting point of the said solid is 82° C. Evaporation of the solvent from the mother liquid leaves the liquid racemic mixture as a residue.

Either the solid or liquid racemic mixture may then be submitted to the following series of reactions:

In Step IV hydrogenation is carried out by known methods, as by means of catalysts as described in the co-pending case referred to above, and these methods need not be elaborated. The same is true of the demethylation of Step V, which may be accomplished, for example, in the presence of inorganic mineral acids as described in the co-pending case, or by means of inorganic bases as set forth below.

Application of Steps III to V to the solid racemic mixture produced as per Step II results in a compound having the formula shown as produced in Step V in the form of two solid racemic mixtures, both of which are crystalline, one having a melting point of 160° C. and the other a melting point of 144° C., which may be separated.

ed by fractional crystallization. It has been discovered that the product having the highest melting point of 160° C. has a higher potency than that having the lower melting point of 144° C. These melting points relate to the specific substance shown as produced in Step V and will be different when the OH radical is in the ortho or meta position and also when it is substituted by other species of the radical X shown in the general formula. The position of the OH group is determined by the corresponding position of the CH_3O group.

Having obtained a phenolic compound as shown in Step V, either or both of the OH radicals may be converted into any desired other species of the general radical X by employing etherification, esterification, or other appropriate methods.

The solid racemic mixture of compounds having the formula of the intermediate compound obtained as shown in Step II is preferred to the liquid racemic mixture obtained in that step, because the conversion of said solid mixture as shown in Steps III to V produces two solid racemic mixtures possessing the action of the follicular hormone in a potency of especially high value. The formula of the compounds in these two solid racemic mixtures is that produced as shown in Step V. To use the solid, but not the liquid mixture would represent a considerable loss in yield of the mixtures produced as shown in Step V because the liquid and solid mixtures are about equal in weight.

This invention includes a further improvement residing in reducing or eliminating this loss in yield, by effecting appropriate changes in configuration in the liquid mixture in respect to one or more of the carbon atoms in the 3-carbon chain connecting the aromatic nuclei. One method is to enolize the liquid racemic mixture produced in Step II to change the configuration of the middle carbon atom in the 3-carbon chain. For example, by enolizing the liquid racemic mixture obtained by Step II it is possible to change it, at least partially, into the solid mixture and then subject the latter to Steps III to V as above explained, and thus increase the yield of the racemic mixtures having highest potency.

Specific details of carrying out Steps I to V above are given as follows:

Step I.—Into a mixture of 100 grams of p-methoxy butyrophenone and 74 grams anisaldehyde, maintained at 15–20° C., dry hydrogen chloride gas is bubbled until the total weight is increased by 20 grams. The thick mass resulting is allowed to stand over night, is then heated to 130–150° C. until all water and hydrogen chloride has been driven off, and is finally distilled under reduced pressure. Following a small amount of lower-boiling forerun, the desired 4,4-di-methoxy- α -ethylchalcone distills at 190–200° C. under 1 mm. pressure. It is a bright yellow oil.

Step II.—A solution of 178 grams (0.6 mole) of the above chalcone in 500 cc. of dry ether is added slowly to a well-stirred solution of 140 grams (1.8 moles) of ethyl magnesium bromide in 1200 cc. of dry ether maintained below –7° C. After addition is complete stirring is continued for three hours at room temperature and the mixture is then poured into 3 liters of ice water containing 150 cc. of concentrated sulfuric acid. The ether layer is separated, the aqueous solution extracted once with ether, the combined solutions dried and the ether distilled therefrom. The entire residue is then distilled at 1 mm. pressure and the distil-

late dissolved in 800 cc. of warm ethanol. From this solution, on standing over night in the refrigerator, the solid isomer (A) of 1,3-di-(p-methoxy-phenyl)-2-ethyl pentanone-1 separates.

5 After filtration and recrystallization from ethanol, this fraction weighs 72 grams and melts at 82° C. A second isomer (B) may be obtained by evaporation of the ethanol from the above filtrate and distillation of the residue under reduced pressure. It is a pale yellow oil.

Step III.—55 grams of the solid form (A) of 1,3-di-(p-methoxy-phenyl)-2-ethyl pentanone as prepared in Step II is dissolved in 300 cc. of dry ether and added slowly to a stirred solution of 55 grams of methyl magnesium iodide in 350 cc. of dry ether. The reaction mixture is refluxed on the steam bath for five hours and then poured into 2 liters of ice water containing 200 cc. of concentrated hydrochloric acid. The ether layer is separated, the aqueous solution extracted once with ether, the combined solutions dried and the ether distilled therefrom. The primary reaction product which remains is heated at 150° C., whereupon water is evolved. The resulting final product is 2,4-di-(p-methoxy phenyl)-3-ethyl hexene, and is obtained on vacuum distillation, in a yield of 50 grams, as a colorless oil which boils at 180–182° C. under 1 mm. pressure.

Step IV.—A solution of 25 grams of the above described 2,4-di-(p-methoxy phenyl) - 3 - ethyl hexene in 140 cc. of glacial acetic acid is subjected to catalytic hydrogenation in the presence of 0.2 gram of platinum catalyst until one molecular equivalent of hydrogen has been absorbed. The solution is then filtered free of the catalyst, diluted with water and neutralized with sodium hydroxide. The product is extracted into ether, the solution dried, and the ether distilled off. The residue is 2,4-di-(p-methoxy phenyl)-3-ethyl hexane. It is a colorless oil.

Step V.—A mixture of 7 grams of 2,4-di-(p-methoxy phenyl) -3-ethyl hexane (as prepared in Step IV) with 14 grams of potassium hydroxide and 25 cc. of 95% ethanol is heated at 200° C. for 45 18 hours in a rocking autoclave. The resulting thick, clear liquid is diluted with water and filtered with charcoal to remove a slight turbidity, and the filtrate is acidified. The precipitate is extracted into ether, the solution dried and the ether distilled off. The residue may be sublimed in a high vacuum. From this sublimate two isomeric compounds can be obtained by fractional crystallization from benzene. Both are white solids and have the structure 2,4-di-(p-hydroxy phenyl)-3-ethyl-hexane. One of the isomers has a melting point of 160° C. and the other a melting point of 144° C.

Although in the above specific examples, separation of the racemic mixtures is effected by fractional crystallization, it is evident that where warranted, other methods of separation, e. g. distillation, use of selective solvents and any suitable method of fractionation may be employed, as will be apparent to those skilled in the art in the light of the invention herein described and claimed. In some cases the mixtures crystallize out as two solid isomers, in which case fractional crystallization may be resorted to. When the isomers are both liquid, fractional distillation may frequently be employed.

As stated at the beginning, the radicals R in the formulas may be any alkyl radicals. In support of this generic statement the following specific examples of compounds having estrogenic and bactericidal properties are given. These

compounds and their corresponding ethers can be prepared by the methods above disclosed. The ethers and esters can be prepared by applying standard etherification or esterification technique to the said hydroxy compounds.

It is preferred that the number of carbon atoms in each of the alkyl substituents on the propane bridge be not greater than five, although the activity of compounds having substituents higher in the series is demonstrated by numerous examples, some of which are included herein.

A specific example of the conversion of one of the hydroxy compounds to the corresponding ester is as follows:

One gram of 2,4-di-(p-hydroxy phenyl)-3-ethyl hexane is refluxed for 3½ hours with a mixture of 10 cc. of propionic anhydride and 0.5 gram of fused sodium propionate. The reaction mixture is diluted with water and made alkaline with potassium hydroxide, and the product is extracted in ether. After removal of the ether the desired ester is obtained as a thick yellow oil which has a boiling point of 185-190° C. at 0.5 mm. pressure.

As many apparently widely different embodiments of this invention may be made without departing from the spirit and scope thereof, it is to be understood that we do not limit ourselves to the specific embodiments thereof except as defined in the appended claims.

We claim:

1. Process for preparing estrogenic compounds which comprises treating

with

wherein R is alkyl and R₁ is selected from the class consisting of H and alkyl, in the presence of an agent selected from the class consisting of inorganic mineral acids and inorganic bases, thereby forming a compound of the formula

10 treating the latter in the cold with R₂MgX, wherein R₂ is alkyl and X is any halide except fluoride, thereby forming solid and liquid isomers of a diphenyl propanone represented by the formula

separating the solid from the liquid isomers 20 thereof, treating the solid isomers under refluxing conditions with R₃MgX, where R₃ is an alkyl group and X is the same as before, thereby producing a compound of the formula

hydrogenating the latter in presence of a hydrogenation catalyst to a compound of the formula

30 and deetherifying this compound in the presence 35 of a material selected from the group consisting of inorganic mineral acids and inorganic bases, thereby forming a compound of the formula

2. Process for preparing estrogenic compounds which comprises treating

with

wherein R is alkyl and R₁ is selected from the class consisting of H and alkyl, in the presence of an agent selected from the class consisting of 55 inorganic mineral acids and inorganic bases, thereby forming a compound of the formula

60 treating the latter in the cold with R₂MgX, wherein R₂ is alkyl and X is any halide except fluoride, thereby forming a mixture of stereoisomers of a diphenyl propanone represented by 65 the formula

70 separating the stereoisomers into racemic pairs, subjecting the pairs separately to a course of treatment comprising reacting a racemic pair of stereoisomers under refluxing conditions with 75 R₃MgX, where R₃ is an alkyl group and X is the

same as before, thereby producing a compound of the formula

hydrogenating the latter in presence of a hydrogenation catalyst to a compound of the formula

and deetherifying this compound in the presence of a material selected from the group consisting of inorganic mineral acids and inorganic bases, thereby forming a compound of the formula

3. Process for preparing estrogenic compounds which comprises treating

with

wherein R is alkyl and R1 is selected from the class consisting of H and alkyl, in the presence of an agent selected from the class consisting of inorganic mineral acids and inorganic bases, thereby forming a compound of the formula

treating the latter in the cold with R3MgX, wherein R2 is alkyl and X is any halide except fluoride, thereby forming solid and liquid isomers of a diphenyl propanone represented by the formula

separating the solid from the liquid isomers thereof, treating the solid isomers under refluxing conditions with R3MgX, where R3 is an alkyl group and X is the same as before, whereby there is produced a compound of the formula

hydrogenating the latter in presence of a hydrogenation catalyst to a compound of the formula

and deetherifying this compound in the presence of a material selected from the group consisting of inorganic mineral acids and inorganic bases, thereby forming a compound of the formula

4. Process for preparing estrogenic compounds which comprises treating

5 with

10 wherein R is alkyl and R1 is selected from the class consisting of H and alkyl, in the presence of an agent selected from the class consisting of inorganic mineral acids and inorganic bases, thereby forming a compound of the formula

treating the latter in the cold with R2MgX, wherein R2 is alkyl and X is any halide except fluoride,

20 thereby forming a mixture of stereoisomers of a diphenyl propanone represented by the formula

25 separating the stereoisomers into racemic pairs, subjecting the pairs separately to a course of treatment comprising reacting a racemic pair of stereoisomers under refluxing conditions with R3MgX, where R3 is an alkyl group and X is the same as before, whereby there is produced a com-

30 pound of the formula

35 hydrogenating the latter in presence of a hydrogenation catalyst to a compound of the formula

40 and deetherifying this compound in the presence of a material selected from the group consisting of inorganic mineral acids and inorganic bases, thereby forming a compound of the formula

45 5. Process for preparing estrogenic compounds which comprises treating anisaldehyde with p-

methoxy butyrophenone in the presence of hydrogen halide, thereby forming 4,4-dimethoxy-alpha-ethylchalcone; treating the latter in the cold with ethyl magnesium halide except the fluoride,

55 thereby forming solid and liquid isomers of 1,3-di(p-methoxyphenyl)-2-ethyl-pentanone-1; separating the solid from the liquid isomers thereof, treating the solid isomers under refluxing conditions with methyl magnesium halide except the

60 fluoride, whereby there is produced 2,4-di(p-methoxyphenyl)-3-ethyl hexene; hydrogenating the latter compound in the presence of a hydro-

65 genation catalyst to 2,4-di(p-methoxyphenyl)-3-ethyl hexane; and deetherifying the last named compound in the presence of a material selected from the class consisting of inorganic mineral acids and inorganic bases, thereby forming 2,4-

di(p-hydroxyphenyl)-3-ethyl hexane.

RALPH C. TALLMAN.

ALFRED H. STUART,
